UNITED STATES PATENT OFFICE

2,382,429

CABINET WITH DRAWERS

Felix F. Loeb, Chicago, and James E. Bales,
Aurora, Ill., assignors to Lyon Metal Products,
Incorporated, Aurora, Ill., a corporation of Illinois

Original application October 14, 1938, Serial No.
234,868. Divided and this application January
27, 1941, Serial No. 376,145

3 Claims. (Cl. 45—77)

This invention relates to display or merchandise racks for supporting and storing merchandise of the type comprising a multiplicity of various parts and assemblies.

The present application is a division of prior application Serial No. 234,868 filed October 14, 1938, Patent No. 2,255,744, issued September 9, 1941.

Among the objects of the present invention is to provide a drawer structure and slide construction for a display stand which is rigid, simple to manufacture from sheet metal, and easily operable from closed to open position.

Another object of the invention resides in providing a drawer structure for display stands or racks wherein the drawer construction is formed so as to readily receive and support a plurality of dividing panels.

Another object of the present invention is to provide a drawer structure which includes lateral uprights or partition members having horizontally disposed, inwardly extending, free edges which edges have reversely bent, resilient portions along which the bottom of the drawer is adapted to slide so as to provide a trackway of some resiliency for slidably supporting the drawer.

These and other objects of the invention will be apparent from a perusal of the following specification when taken in connection with the accompanying drawings:

Figure 1 is a perspective view of the rack which provides an improved drawer structure;

Figure 2 is a view of one of the drawers;

Figure 3 is a section taken along the line 3—3 of Figure 1;

Figure 4 is a section taken along the line 4—4 of Figure 1; and

Figure 5 is a plan section taken on the line 5—5 of Figure 4.

Figure 6 is a fragmentary perspective view of the lefthand corner of the display rack, with a portion of the top broken away to show the drawer supporting and guiding means, the drawers being removed therefrom.

Referring now to the drawings in detail, only the upper portion of the display rack is shown in Figure 1; it is shown as being provided with two sides, a back and a top, and with a display shelf immediately beneath the two drawers which form the subject matter of the present invention. The other features herein claimed form the subject matter of divisional co-pending applications.

The sides of the table unit are provided with a pair of side wall members adapted to support the

shelf, trough, and drawer structures, as well as a top enclosing wall. The side wall members are mounted along opposite side edges of a bottom or floor (not shown). More particularly, each of the side walls comprises an outer panel 24 of sheet material and an inner panel 26 spaced therefrom. The forward upstanding edge of the inner panel member provides a suitable molding 32 along the vertical edges of the side wall members at the front of the rack, same being disclosed in a co-pending application, Serial No. 376,146, filed January 27, 1941.

The back wall of the assembly consists of a sheet panel member 44 bolted along either side edge to suitable flanges to the inner extremities of the inner side panel 26. The top wall of the present display or merchandising cabinet comprises a substantially flat horizontal sheet member 46 having both side edges, as well as its rear edge, formed downwardly as at 48, and providing an inwardly, offset vertical flange 50, to which are rigidly bolted upright walls 44 and 26 through the agency of machine bolts 52. The front edge of the wall 46 terminates in a downwardly projecting flange 58. The upper side edges of the unit are provided with encasing rectangular finished molding pieces. The molding piece on the front consists of the longitudinally extending sheet member 60 formed to a substantially rectangular sectional configuration open on one side (see Figure 3) to fit over the forward edge of the top wall and is secured to the downwardly extending flange 58 by welding. Corresponding rectangular molding pieces 62 are fastened along the side flanges 48 by means of any desired fastening means.

The present invention further comprehends the inclusion of drawer structures adapted to support merchandising elements in predetermined relationship with the top and shelf assemblies. The drawer structure herein shown comprises a plurality of drawers 128 mounted upon transversely extending strips 186, which are secured to the side wall panels 26. Longitudinally extending channel members 188 embrace the drawers on either side thereof, the lower flanges of each of the channel members having an edge which is reversely bent as at 190 forming a trackway of some resiliency for slidably supporting the drawers.

The channels 188 are joined together by angle members 192 positioned laterally thereon and secured to the upper channel flanges 189 through the agency of rivets 194. The bottom wall 130 of each of the drawers is bent up at its rear edge to provide the rear wall 196 of the drawer while

the lateral side edges are similarly upwardly flanged as at 198 for joining with side walls 200 by means of welding or other type of fastening.

A front wall or face for the drawer is provided by the sheet wall member 202 extended downwardly beyond the bottom wall of the drawer as at 204, thereby providing a flange 206 for securing to said bottom wall 130, and, likewise, providing a stop. Each of the side walls of the drawer comprises a reversely bent or double sheet of material, preferably metal, the inner layer or sheet of which is formed outwardly as at 208 to provide an offset portion forming a rectangular enclosure. This offset portion 208 is severed or slit at spaced points 210 to provide for engagement with transverse partition walls 212. In the embodiment shown, each of the drawers is divided by rearwardly extending partition walls or dividers 214.

Parallel with the side walls and secured to the bottom wall of the drawer by means of the bent-over tabs 216 and to the rear wall by the fasteners 218, a sheet enclosing member 220 formed about each partition wall 214 is similarly configurated on opposite sides of said wall into the rectangular protruding wall 208, which is similarly slit as at 210 for the same purpose. The transverse partition walls 212 are flanged at the bottom as at 222 and are of such length to extend into opposed slits or recesses 210.

The bottom supporting flange 222 terminates short of either end of the partition member 212, so that the partitions may be selectively arranged in any opposed pair of slits or recesses 210 by vertically sliding them into position. The recesses 210, where they pass through the horizontal walls of the offset portion 208, are substantially circular to accommodate deformed end portions 224 adapted to additionally engage the transverse partitions for rigidly holding them in position.

The drawers are slideable on the tracks formed by the flanges 190 and are laterally guided by the channel members 183. The angle bracket 226 fastened to the bottom wall by means of a screw 228 limits the outward movement of the drawer by abutment with the forward drawer supporting strap 186.

In the embodiment herein shown there are two drawers, each of which is positioned above a corresponding compartment on the under shelf 76, which compartments are designated and separated by a partition 88. The present merchandising rack accordingly may be used by storing or placing separate main assemblies on either side of the partition 88 on the shelf, and storing the associated parts in the respective vertically aligned drawers and trough compartments in advance of the shelf portion 76.

Changes may be made in the form, construction and arrangement of the several parts without departing from the spirit or scope of the invention, or sacrificing any of its attendant advantages, the form herein described being a preferred embodiment for the purpose of illustrating the invention.

Having thus described our invention, what we claim as new and desire to secure by Letters Patent is:

1. In a display cabinet or the like, the combination of spaced upright sides and a top providing a drawer housing, fixed supports extending horizontally between said sides and rigidly affixed thereto, spaced upright brackets each having a vertical portion formed with an upper horizontal flange and a lower horizontal flange, each lower flange being welded to said supports and each having beyond said welded portion a reversely bent resilient free edge overlying and spaced from said lower flange, and a drawer having sides, a rear end, a front and a bottom disposed between said spaced brackets with the bottom of the drawer slidably resting upon said reversely bent free edges.
2. In a display cabinet or the like, the combination of spaced upright sides and a top providing a drawer housing, supports extending horizontally between said sides and affixed thereto, spaced upright brackets each having a vertical portion formed with an upper horizontal flange and a lower horizontal flange, each lower flange being welded to said supports and each having a reversely bent portion terminating in a resilient free edge overlying said lower flange, a drawer having sides, a rear end, a front and a bottom disposed between said spaced brackets with the bottom of the drawer slidably resting upon said reversely bent free edges, and an angle iron overlying the upper flanges of said spaced upright brackets and fastened thereto.
3. A display cabinet or the like comprising spaced vertical sides and a top forming a drawer housing, transverse supports horizontally disposed between said sides and fixed thereto, a pair of spaced side brackets extending substantially the depth of the housing and disposed between said transverse supports and the top of said housing, each bracket comprising a basal flange welded to the horizontal upper surface of each support and each bracket including a vertical wall, and an additional, inwardly extending upper horizontal flange spaced from said basal flange, and a pair of such brackets disposed intermediate the said outside brackets, said intermediate brackets being disposed with their vertical walls disposed back to back and with their upper and lower flanges extending reversely toward the upper and lower flanges of said outside brackets, and rigidifying members attached to the upper flanges of said brackets, the basal flange of each bracket having a reversely bent, spaced, resilient edge overlying the flange and providing a resilient slideway and a pair of drawers disposed between said spaced pairs of brackets, the bottom of each drawer being resiliently and slidably supported on the resilient, reversely bent edges of the spaced flanges.

FELIX F. LOEB.
JAMES E. BALES.
